UNITED STATES PATENT OFFICE.

KARL OTTING, OF BERLIN, GERMANY.

BAG OPENING AND FILLING MACHINE.

Original application filed May 12, 1921, Serial No. 468,866. Divided and this application filed May 16, 1922. Serial No. 561,509.

(GRANTED UNDER THE PROVISIONS OF THE ACT OF MARCH 3, 1921, 41 STAT. L., 1313.)

To all whom it may concern:

Be it known that I, KARL OTTING, a citizen of the German Republic, and a resident of Berlin, Germany, have invented certain new and useful Improvements in Bag Opening and Filling Machines, of which the following is a specification, and for which I have obtained German Patents 345,029, on Sept. 27, 1921, and 349,417, on December 30, 1921, both patents being granted on an application filed April 26, 1919, and British Patent 157,320, on June 28, 1921, on application filed January 10, 1921 (the present application being divided out of my copending patent application Serial No. 468,866, filed May 12, 1921).

In bag opening and filling machines provided with rotatable bag openers it is very difficult to effect in a reliable manner, that the bag openers in every turn take a bag from the pile of bags and that then one opener after the other presents to the filling device a bag without fail.

According to this invention the bags are piled within a magazine vertically upon one another so that they can be withdrawn from underneath. The lowest bag is stripped from the magazine by the respective opener under the weight of the pile of the bags resting upon it, and thus it is not necessary to have separate weights for pressing down the bags in the magazine. With the latter co-operates a turret carrying the bag openers in such a manner that a number of similar bag openers are moved one after the other into a horizontal position for withdrawing the bags from the vertical pile, and during the intermittent stopping of the machine are held in such a manner that the vertically and horizontally moved magazine pushes the lowest bag on to the horizontally presented bag opener and then moves away from the latter.

As the turret carrying the bag openers continues its movement, the bag openers together with the bags slipped on to them are brought again into a vertical position, and present the bag to the filling hopper, whereupon after a further movement the filled bags are delivered to a closing device or may be closed by hand.

A constructional example of this inven-

tion is illustrated in the accompanying drawing in which

Fig. 1 is a side elevation thereof and Fig. 2 a plan view.

The bag magazine *a* for the bags *a'*, which are placed in said magazine with the part to be flapped directed upwardly, and are lying upon one another in a vertical pile, is guided along a bar *b*. The bar *b* is fixed to a slide *b'* which is guided vertically in the frame *c*. The frame *c* is bolted to the base plate *d*.

The rotational motion is transmitted from the main shaft *m* which latter is driven by a pulley *m'*. The main shaft *m* transmits its rotation by a chain gearing *n*, *n'*, *o* to the shaft *e* and hence by a bevel gearing *e'* and a chain gearing *e''* to the shaft *w*. The shaft *w* carries a cam *b*² engaging with a roll *b*³ of the slide *b'*. By the rotation of the cam *b*² the bag magazine *a* is raised and lowered. On the shaft *w* there is further mounted a crank *a'*, which by means of the connecting rod *a*² moves the bag magazine to-and-fro along the bar *b*.

This motion is such that the bag magazine *a* pushes the lowest bag on to the horizontal bag opener *f* presented to it and then moves away from the said opener. Owing to the influence of the cam *b*² and the crank *a'* the motion of the bag magazine *a* is substantially rectangular.

At the side of the bag magazine *a* there is mounted on the plate *d* the bag opener turret comprising a hollow shaft *z'* provided with arms *z* carrying on shafts *f'* the bag openers *f*, of which for instance four are present. These bag openers are adapted to rock on the shafts *f'* and of being moved by a cam *g*, engaging with the rollers *f*² of the bag openers *f*, alternately into the horizontal position shown at the right hand of Fig. 1, or into the vertical position shown at the left hand of the said figure.

The turret *z'* is rotated in an intermittent motion by means of a bevel gear *m'* and a gear known as Maltese-cross or any other gear producing the same effect. In the example shown a Maltese-cross gear is used; it consists of a locking plate *l'* with a crank *l''* fixed thereon and a cross-wheel *l* on the shaft *z'*. During each revolution of the

main shaft m and of the locking plate l' the cross-wheel l is once engaged by the roll l^3 on the end of the crank l^2 and rotated for the fourth part of a revolution in accordance 5 with the number of bag openers f . It will be understood, that the turret z' is rotated only, after a bag has been pushed on its bag 10 opener f presented to the bag magazine a , and that the turret z' is at standstill during this pushing motion.

After a quarter rotation of the turret z' , the bag openers f together with the pushed-on bag, pass from the position I in Fig. 2 into the vertical position II underneath the filling hopper h which belongs to a filling device of any known construction. In the example shown the hopper h receives the contents for each of the bags from a distributing cylinder t rotating below a larger hopper u containing a stored supply of the material to be filled into the bags. The axle of the cylinder t carries a grooved wheel s , which is engaged by a pin s' on the chain wheel r driven by chain gearing o^1 , o^2 from the shaft e . During the time in which the turret z' is at rest for the purpose of stripping the lowest bag on the bag opener f presented in the horizontal position I to the magazine a , the cylinder t receives a partial revolution in order to deliver a measured quantity of the material through the hopper h and the bag opener f , which has the form of a chute into the bag occupying now the position II. After the filling, the bags pass during a further quarter revolution of the turret z' into a position opposite the closing device (position III). In general the friction between the bags and the openers is sufficiently great to cause the bags to be held firmly upon the bag opener during the movement from position II into position III. However in order to prevent an unintentional sliding off of the filled bag from the bag 40 opener, a safety bar i is provided under their path. Behind each bag opener f there is guided on its carrier f^3 , a stripper f^4 , which in the position III is set in operation

to strip off the bags from the opener f . This is effected by a double lever p' , which is 50 swinging on a pin v and carries on one end a roll p'' entering a U-shaped frame q of the stripper f^4 . The other end of the lever p' is engaged by a cam p on an extension o'' of the shaft e . In the position III of the 55 openers f , the turret z' being at rest the cam p raises the neighbouring end of the lever p' and its other end pushes down the stripper f^4 . The filled bags are received by a guide through i' to be closed in any known manner. 60

Having now particularly described the nature of my invention, what I claim as new and desire to secure by Letters Patent of the United States is: 65

1. A bag opening and filling machine, comprising a bag magazine adapted to receive therein the vertically piled bags, a rotatable bag presenting turret, a plurality of bag openers carried by said turret, a filling 70 device, means for moving the bag magazine relatively to the bag openers and means for swinging the bag openers into one position in order to receive a bag from the bag magazine and to present the bag stripped onto 75 the opener to the filling device in the other position.

2. A bag opening and filling machine, comprising a bag magazine adapted to receive therein the vertically piled bags, a rotatable bag presenting turret, a plurality of bag openers carried by said turret, a filling 80 device, means for moving the bag magazine horizontally and vertically relatively to the bag openers and means for swinging the 85 bag openers into one position in order to receive a bag from the bag magazine and to present the bag stripped onto the opener to the filling device in the other position.

In testimony whereof I affix my signature 90 in presence of two witnesses.

KARL OTTING.
